UNITED STATES PATENT OFFICE.

JOSEPH K. SHARPE, JR., OF INDIANAPOLIS, INDIANA, ASSIGNOR TO THE INDIANA MANUFACTURING COMPANY, OF INDIANAPOLIS, INDIANA, A CORPORATION.

PNEUMATIC STACKER.

No. 902,841.

Specification of Letters Patent.

Patented Nov. 3, 1908.

Application filed April 13, 1908. Serial No. 426,699.

To all whom it may concern:

Be it known that I, JOSEPH K. SHARPE, Jr., a citizen of the United States, residing at Indianapolis, in the county of Marion and State of Indiana, have invented certain new and useful Improvements in Pneumatic Stackers, of which the following is a specification.

Pneumatic stackers as applied to threshing, corn shredding and similar machines are made in varied forms, and particularly in the arrangement and location of the fan or fans for withdrawing and discharging material from such machines, a common type being what is known as the "side fan" stacker, *i. e.*, having its fan arranged vertically at one side of the machine and near the rear end thereof, the straw receiving or ingress opening of the fan communicating with a hopper positioned transversely of the stacker structure into which the material is deposited and then withdrawn therefrom into the fan by the suction air current created by said fan and discharged thereby through the stacker pipe. In such an arrangement, as will be readily understood, the flow of material falling directly vertically toward and into the hopper must be caused to turn abruptly and take a substantially horizontal course in its travel toward and into the fan ingress. In order to positively control and direct this flow in the manner described it is necessary and has been the common practice in some types of such stackers to form the straw chamber or hopper sloping from its opposite and rear and front sides downwardly to the lower portion of the fan eye to insure that material farthest from the fan may by gravity move toward and within the influence of the suction air current, which exists only within a limited area in the hopper immediately adjacent the fan ingress, and be drawn into said fan.

In other types of side fan stackers a horizontally arranged chamber or trough is employed, extending transversely across the structure from wall to wall thereof, the discharge fan being outside the housing, in which cases, by reason of the limited suction created in the trough by the fan, material falling beyond the influence of such current will lie inertly and not move toward the fan, and, therefore, a mechanical conveyer must be employed to urge or deliver material into the current, in some of which conveyers the fan shaft extends through the chamber and

is provided with fingers or other devices capable of moving material, while in others endless carriers are placed in the bottom of the chamber, or other propelling devices for the purpose are provided. It will also be understood that many types of threshing, shredding and like machines are manufactured, each differing in design and proportions and equipped with distinctive separating mechanisms, and each type being made in different sizes, so that the pneumatic stacker, particularly and essentially with reference to its hopper or material chamber construction, must be designed especially for each type and each size, and must be constructed to accurately fit and meet all the conditions existing by reason of height, width and peculiar separating devices employed in the separating machine, and the size, formation and power of the discharging fan, necessitating more or less modification in the pitch, contour and general formation of the hopper, and in the proportion and dimension of conveyers, as such varied conditions and the peculiar type of stacker demand.

The object of my invention is to simplify and improve the construction of such pneumatic stackers whereby the present necessary specially designed mechanical arrangements and devices for directing the material in the hopper toward the influence of the discharging fan will be dispensed with, a uniform and more capacious and unobstructed material chamber provided, and a positive and effective blast draft created through such chamber insuring that all material deposited in any part thereof will be instantly delivered into the discharge fan, all as will be hereinafter more particularly described and claimed.

In the accompanying drawings, which are made a part hereof, Figure 1 is an elevation of a pneumatic stacker structure in position to be attached to the rear end of a separating machine, showing the material-receiving chamber and associated parts; Fig. 2 a rear view showing a manner of driving the blast fan from the shaft of the material discharging fan; Fig. 3 an elevation illustrating the action upon the material produced by said blast fan; Fig. 4 a central sectional view as seen when looking in the direction indicated by the arrows $x-x$ in Fig. 3 but omitting the blast regulator; Fig. 5 a detail showing the

protecting guard for the blast fan; Fig. 6 a detail showing the device employed to regulate the air current from said blast fan; and Fig. 7 a side elevation showing a pneumatic stacker attached to a separating machine and illustrating a manner of driving the blast fan from such machine.

In the drawings, the portions marked 10 represent the housing which constitutes the material-receiving chamber of a pneumatic stacker, in the bottom of which chamber is formed a substantially horizontally arranged concave (or other appropriately formed) receptacle or trough 11 positioned transversely 15 of the structure and communicating with the fan ingress 12 formed in the fan casing 13, which casing, in the type of stacker shown, is formed inside the housing, and, being connected to the material-receiving receptacle 20 or trough 11, forms a substantially integral fan casing and chamber. In the type of stacker thus described it is the practice to employ a gravity hopper inclined in different directions downwardly to the lower portion 25 of the fan ingress opening, while in types where the fan is located outside the housing a receptacle or trough occupies all of the space across the width of said housing, thus providing a maximum trough space, but in 30 such latter types mechanical devices, as heretofore referred to, must be employed to move material from the farthest or "dead" end of the trough into the air currents created by the discharge or burden fan 14. In 35 the arrangement which I employ, as heretofore indicated, the trough 11 is of a simple substantially concave formation extending horizontally from the fan ingress 12 to the opposite wall of the housing in the type illustrated and specifically described, and from 40 wall to wall in the type referred to, and communicates with said fan ingress as shown, while at its opposite end I provide a blast fan 15, protected by a suitable cage or guard 16, 45 accurately positioned within a suitable opening in the wall of the housing and having a band 17 surrounding its periphery, said fan being preferably mounted on a driving-shaft 18, supported by an appropriate bracket, as 50 19, the outer end of said shaft bearing a pulley 20, which, by a pulley 21, is belted to a counter-shaft 22 running across the rear end of the stacker, which shaft at its opposite end is provided with a pulley 23, belted to a pulley 24 on the discharge-fan shaft 25, and which latter shaft is driven from the cylinder or other appropriate driving means associated with the separating machine. By this arrangement I obtain a very simple and effi- 55 cient means for driving the fan 15 from the same source which drives the discharge fan, which fan 15 is mounted and designed to run very lightly, its only office being to propel a blast across the material chamber into the 60 opposite fan, which is accomplished by ar-

ranging it in an opening as shown, so that its vanes, which are slightly inclined and face the opposite fan opening, draw therethrough a sufficient supply of air from the exterior (or from the interior of the machine where 70 practicable so to do) to produce a blast of the required effectiveness, to carry material through the trough to the discharge fan. Although I have shown and described a specific manner by which I may mount and 75 drive said fan 15, I desire to be understood as not limiting myself to such arrangement, as obviously I may locate the counter-shaft 22 at any convenient point, or dispense with such arrangement and drive the blast fan independently from the discharge fan by suitable connection with a rotary element associated with the separating machine and on the same side as said fan 15, as indicated in 80 Fig. 7, where the stacker structure, 26, is 85 shown as attached to a separator, 27, provided at its lower side opposite the tailings elevator with a pulley, 28, driven from the cleaning fan, and which pulley is mounted on a shaft, 29, extending across the separator 90 for driving the tailings elevator, and on which shaft I provide a pulley, as 29', which is belted to the pulley of fan 15 and by which said fan is driven; or where conditions may demand or it becomes preferable I may 95 mount both fans on a single shaft running through the material chamber and drive the same from one side of the separating machine.

I also employ a suitable blast controller 100 or regulator for the blast fan 15 and for which purpose I provide over the inner or outlet side of said fan an adjustable covering, such as the sliding door 30, mounted in guides 31, which, according to the proportion of the fan covered thereby, compresses the blast into greater or less density, so that in discharging dry and light material, where the normal blast is sufficient to drive the same, the door may be opened to its fullest 110 extent, and where such material is wet, sluggish, or heavy and slimy as rice straw, and a more powerful blast is necessary to convey it through the trough, I am enabled to increase the force of such blast to the extent 115 required by diminishing the outlet of said fan to the size desired by adjusting said door accordingly; but it will be understood, of course, that such blast controller need not necessarily be adjustable, as where it is desired to permanently arrange the fan outlet to produce a blast of a specific and unvarying force any suitable means for the purpose may be provided.

I am aware that blast producing devices 125 for a similar purpose have been proposed, but so far as I am informed such blasts have been produced at a point other than directly opposite the discharge fan and conveyed thereto through conduits or otherwise, but 130

I believe myself to be the first to devise means in a pneumatic stacker directly opposite its discharge fan for producing a positive and variable blast draft in the manner 5 and operating as described, and I have successfully demonstrated that a blast fan such as described, when arranged directly opposite the discharge-fan ingress, creates a powerful air current in the material chamber, which, combining with the limited suction air current created by the discharge fan, produces a positive and continuous draft through the entire chamber of such area, 10 velocity and effectiveness as to instantly convey all falling material into the discharge fan; and the accomplishment of such result in the manner described is of great advantage and importance, as the proper directing and delivery into the discharge fan of 15 such material as straw, which is in ever varying condition, at times being dry and fluffy, damp or wet, and falling in straggling and uneven masses or bunches, is very difficult and by some methods uncertain, and 20 this is particularly so with reference to rice straw, which, when threshed, is in wet and slimy condition, and adheres to and clogs the straw chamber, requiring an attendant to manually agitate and loosen such material 25 to keep it moving into the discharge fan. Furthermore, the stacker or discharge fan as now commonly employed must be driven at an exceedingly high speed in order to accomplish its double work of creating a suction current capable of withdrawing material 30 from the chamber, and discharging such material through the stacker pipe. By my improved arrangement, however, the discharge fan is relieved of much of its 35 burden, as the speed thereof may now be reduced to produce the minimum centrifugal action required to eject its load, without reference to great rapidity for creating a maximum intake or suction air current, for 40 the reason that when an adequate centrifugal force is attained there is at the same time present at the fan ingress an intake current sufficient to coöperate with the blast from the opposite fan to establish a 45 continuous draft through the material chamber to properly convey and direct the material into the discharge fan; and this reduction of speed and consequent saving of power is of great moment in such a machine as a thresher, 50 with its multiplicity of rotary and reciprocatory elements and many special attachments, which heavily tax its prime motor, and where economy of power in any direction is to the betterment of the whole outfit.

60 I claim as my invention:

1. The combination, in a pneumatic stacker, of a material-discharging fan at one side thereof, an unobstructed material-receiving receptacle forming a free and uninterrupted passageway for air and material

and communicating at one end with said fan, and a fan at the opposite end of said receptacle for creating and discharging an air blast through said receptacle for pneumatically conveying material therethrough and to said discharge fan. 70

2. The combination, in a pneumatic stacker, of a material-discharging fan at one side thereof, a substantially concave horizontally - arranged material - receiving trough forming a free and unobstructed passageway for air and material and communicating at one end with said fan, and a fan at the opposite end of said trough for creating and discharging an air blast through said trough 75 for pneumatically conveying material therethrough and to said discharge fan.

3. The combination, in a pneumatic stacker, of a material-discharging fan at one side thereof, a material-receiving receptacle 80 communicating with said fan, a blast fan at the opposite side of said receptacle, and means associated with said blast fan for regulating the air current produced thereby.

4. The combination, in a pneumatic stacker, of a material-discharging fan at one side thereof, a material-receiving receptacle communicating at one end with said fan, a blast fan at the opposite end thereof, and an adjustable door for diminishing or increasing 95 the force of the air blast from said blast fan.

5. The combination, in a pneumatic stacker, of a material-discharging fan at one side thereof, a material-receiving receptacle 100 communicating at one end with said fan, and a blast fan at the opposite end of said receptacle arranged to receive its air supply through the wall thereof directly from the exterior and to produce a blast draft in and through said receptacle. 105

6. The combination, in a pneumatic stacker, of a material-receiving chamber, a material-discharging fan at one side thereof, a driving shaft for said fan, a fan at the opposite side of said chamber, and mounted independently of said discharge fan, and means for driving said last mentioned fan from the shaft of said discharge fan. 110

7. The combination, in a pneumatic stacker, of a material-receiving chamber, a material discharging fan at one side thereof, a shaft for said fan, a fan at the opposite side of said chamber, a shaft for the latter fan, a countershaft, means connecting said countershaft with said discharge fan, and means connecting said countershaft with said oppositely - arranged fan whereby both of said fans are driven from a single source. 115 120

8. The combination, in a pneumatic stacker, of a material-receiving chamber, a fan mounted on each side thereof and independently of the other, and means for operating each of said fans independently of the other. 125

9. In a pneumatic stacker, the combina- 130

tion of a material-receiving chamber, an incased burden fan at one side thereof, and a fan at the opposite side of said chamber arranged to draw its air supply through the wall thereof directly from the exterior and to create a blast draft through said chamber toward said burden fan for conveying material across said chamber into said fan.

10. A pneumatic stacker comprising a housing, a material discharging fan at one side thereof, a blast fan in the opposite side of said housing the radiating vanes whereof are disposed to face said discharging fan, means for rotating said discharging fan, and 15 means for rotating said blast fan independently of said discharging fan.

11. A pneumatic stacker comprising a housing, a material-discharging fan at one side of said housing, a receptacle positioned 20 transversely of said housing and communicating with said fan, a blast fan in said housing opposite said discharging fan, and a protecting guard for said blast fan.

12. A pneumatic stacker comprising a material-receiving chamber, a discharge fan at one side of and communicating with said chamber and producing a suction air current therein, and a blast fan in the opposite side of said chamber arranged to produce a positive air blast in a direction parallel with its shaft through said chamber and into said

discharge fan whereby material within said chamber is conveyed entirely pneumatically therefrom into said discharge fan.

13. A pneumatic stacker comprising a material-receiving chamber, a substantially horizontally - arranged interiorly unobstructed trough therein, a discharge fan in one side of said chamber, and a fan associated with the opposite side of said chamber 35 for creating a blast and discharging the same throughout the entire length and breadth of said trough for pneumatically conveying material therefrom into said discharge fan.

14. The combination, with a separating machine, of a pneumatic stacker at the rear end thereof embodying a material-receiving chamber, a substantially horizontally - arranged trough in said chamber, a discharge fan at one side of said separating machine, 50 and an independently mounted fan located in the opposite side of said machine and arranged to convey a blast of air throughout the entire length and breadth of said trough for conveying material pneumatically into 55 said discharge fan.

In testimony whereof I affix my signature in presence of two witnesses.

JOSEPH K. SHARPE, JR.
